CLAIM

The ornamental design for a multiple effect pyrotechnic shell, as shown and described.

DESCRIPTION

FIG. 1 is a perspective view of the a multiple effect pyrotechnic shell according to the present invention;

FIG. 2 is a side elevational view of the shell of FIG. 1;

FIG. 3 is a front elevational view of the shell of FIG. 1;

FIG. 4 is a rear elevational view of the shell of FIG. 1;

FIG. 5 is a top plan view of the shell of FIG. 1; and,

FIG. 6 is a bottom plan view of the shell of FIG. 1.

The broken line showing of a lift chamber, a fuse, and a fuse support loop, in FIGS. 1-4, a fuse support and fuse support loop in FIG. 5, and a lift chamber and fuse support in FIG. 6, is for illustrative purposes only and forms no part of the claimed design.
